US00D730863S

(12) **United States Design Patent**
Yamagishi et al.

(10) **Patent No.:** **US D730,863 S**
(45) **Date of Patent:** **** Jun. 2, 2015**

(54) **MOBILE PHONE**

(71) Applicant: **Sony Mobile Communications AB**,
Lund (SE)

(72) Inventors: **Asami Yamagishi**, Beijing (CN); **Wei Huang**, Beijing (CN)

(73) Assignee: **Sony Mobile Communications AB**,
Lund (SE)

(**) Term: **14 Years**

(21) Appl. No.: **29/472,201**

(22) Filed: **Nov. 9, 2013**

(30) **Foreign Application Priority Data**

Jun. 6, 2013 (EM) 001373609-0001

(51) **LOC (10) Cl.** **14-03**

(57) **CLAIM**

The ornamental design for a mobile phone, as shown and described.

DESCRIPTION

FIG. 1 is a perspective view of a mobile phone showing our new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

1 Claim, 7 Drawing Sheets
